CLAIM

The ornamental design for a bottle, as shown and described.

DESCRIPTION

FIG. 1 is at top, front, and right side perspective view showing my new design for a bottle;

FIG. 2 is a bottom plan view thereof;

FIG. 3 is a top plan view thereof; and,

FIG. 4 is a front elevational view thereof, the rear and side elevational views being identical.

The broken line showing of the bottom of the bottle in FIG. 2 is included for the purpose of illustrating only and forms no part of the claimed design.
